ARCH SUPPORT

Joseph C. Howell, Fort Lee, N. J.

Application December 4, 1936, Serial No. 114,225

8 Claims. (Cl. 36—71)

This invention relates to arch supports and has particular reference to an improved assemblage of adjustably connected units for the metatarsal and longitudinal arches of the foot.

5 The invention has for its principal purpose, an assemblage of resilient arch supporting units for the metatarsal and longitudinal arches of the foot which units are adjustable longitudinally, transversely and angularly and which includes 10 means adapted to connect the arches together and to engage with the sole of the shoe for anchoring the same against movement.

More particularly the invention includes arch supporting units having extensions adapted to 15 overlap, and means for connecting the same which permits of selective adjustment of the units with respect to each other and for anchoring the units to the shoe in adjusted relation.

The invention further provides arch supporting 20 units for the metatarsal and longitudinal arches of the foot, the unit for supporting the longitudinal arch extending forwardly from a point overlying the heel of the shoe and terminating at a point alongside of the metatarsal 25 arch of the foot with the forward portion thereof provided with a concave inner edge for receiving and accommodating the adjacent side edge of the metatarsal unit so that the said arches merge one with the other, together with means for adjustably connecting the arches together and for 30 anchoring the same to the sole of the shoe.

The invention further comprehends in one of its units a flexible member, a resilient arch plate underlying and connected to the said member, a 35 tension plate underlying the said arch plate and connected therewith at its ends for effecting a differential upward arching of the arch plate and means engageable therewith for adjustably anchoring the same to the shoe sole.

40 The invention further includes in one of its forms, an arch supporting member comprising upper and lower plies of material connected together at their edges to define a pocket therebetween for selectively receiving filler pads for 45 effecting differential upward arching of the upper ply and means of connection between the units which permits of the relative adjustment of the units and the pivotal adjustment of the metatarsal unit at a plurality of longitudinally 50 and transversely spaced points, together with means engaging with the said units and with the sole of the shoe for securing said adjustments with the units disposed in any desired position on the sole of the shoe.

55 In the drawings:

Fig. 1 is a bottom plan view of arch supporting units for the metatarsal and longitudinal arches of the foot embodying one form of the invention and illustrated in relative position to a shoe shown in broken lines.

Fig. 2 is an inner edge view thereof showing the same in applied position.

Fig. 3 is a transverse sectional view on line 3—3 of Fig. 1.

Fig. 4 is a plan view of the upper member of 10 the longitudinal arch supporting unit.

Fig. 5 is a plan view of the lower spring plate of the said arch supporting unit.

Fig. 6 is a bottom plan view of the metatarsal arch supporting unit separated from the longitudinal arch supporting unit.

Fig. 7 is a top plan view of a modified form of metatarsal and longitudinal arch supporting units illustrated in applied position with reference to the shoe shown in broken lines.

Fig. 8 is an outer edge view thereof in applied position.

Fig. 9 is a top plan view of the tension plate of the longitudinal arch supporting unit.

Figs. 10, 11 and 12 are top plan views of the 25 spring metal plates forming a part of the said longitudinal arch supporting unit.

Fig. 13 is a longitudinal sectional view through the metatarsal arch supporting unit on line 13—13 of Fig. 14.

Fig. 14 is a bottom plan view of the metatarsal arch supporting unit.

Fig. 15 is a fragmentary enlarged sectional view on line 15—15 of Fig. 8.

Fig. 16 is a top plan view of a modified form 35 of metatarsal arch supporting unit.

Fig. 17 is a bottom plan view thereof.

Fig. 18 is a longitudinal sectional view taken on the line 18—18 of Fig. 17.

Fig. 19 is a transverse sectional view taken on 40 the line 19—19 of Fig. 17.

Referring to the drawings by characters of reference and more particularly to the form of the invention illustrated in Figs. 1 to 6 inclusive, the arch supporting device includes a 45 metatarsal arch supporting unit 10 and a longitudinal arch supporting unit 11.

The metatarsal arch supporting unit 10 is of general oval formation in contour with a rearwardly directed convergent shank portion 12 and 50 includes a flat lower surface 13 and a convex upper surface 14. The said arch support is provided with an attaching member 15 fashioned from deformable sheet metal, leather or any other equivalent material and which is formed 55

with a plurality of longitudinally and transversely spaced openings 16 underlying the shank portion 12 thereof and with a bifurcated forward end secured to the under surface 13 of the unit 5 by rivets 17 or other equivalent securing means, the furcations of said forward end being provided with longitudinally extending slots 18 functioning to increase the flexibility of the said member.

10 The longitudinal arch supporting unit 11 includes an upper member 19 constructed from deformable sheet metal, leather or any other equivalent material and extends from a point overlying a portion of the heel of the shoe forwardly thereof under the inner longitudinal arch of the foot to a point alongside of the metatarsal arch supporting unit 10. The upper member 19 is provided in the forward end thereof with a concave inner edge portion 20 for receiving and 15 accommodating the adjacent side edge of the metatarsal unit so that the same may be positioned in close relation merging one with the other in the region of the metatarsal arch.

In order to provide means for connecting the 25 arch supporting unit 11 with the arch supporting unit 10 by a common securing element, the inner side edge of the upper member 19 is provided with a lateral extension 21 intermediate the ends thereof which is formed with a plurality 30 of longitudinally and transversely spaced openings 22 and which extension is adapted to be arranged in lapped relation with the attaching member 15 of the arch supporting unit 10 with any one of the openings 16 thereof in registration 35 with any one of the openings 22 of the upper member 19. The inner side edge 23 of the upper member 19 extends rearwardly and outwardly from the extension 21 at an angle to the outer side edge 24 and provides a substantially pointed rear terminal 25.

40 In order to increase the flexibility of the portion of the upper member 19 in the region of the edge 23, the same is formed with longitudinally spaced inwardly extending slits 26 when the member 19 is of metal. The forward terminal 27 45 of the upper member 19 is of a width to provide a substantial bearing surface at the forward end of the arch unit 11 and in order to afford the desired flexibility at the medial portion of the said upper member 19, the same is provided with longitudinally extending transversely spaced slots 28 when the said member is formed of metal.

50 The arch supporting unit 11 also includes a spring metal plate 29 underlying the upper member 19 and which is longitudinally arched with the highest point thereof under the inner longitudinal arch of the foot and which decreases in height towards the opposite ends thereof and laterally towards the inner curved side edge with its terminal ends welded as at 30 or otherwise secured to the terminal ends 25 and 27 respectively. The arch plate 29 is of general triangular formation in contour, with its greatest width substantially intermediate the ends thereof and 55 with the forwardly and rearwardly directed inner side edge portions 31 and 32 extending outwardly and at an angle to the outer side edge 33 thereof and which edge portions are welded or otherwise secured to the upper member 19 as at 70 34. In order to render the medial portion thereof more flexible, the inner side edge thereof is slotted as at 35 so as to provide an elliptical tongue 36 which is formed with a plurality of longitudinally spaced transversely extending slots 37.

75 Underlying the spring metal plate 29 is a simi-

larly longitudinally arched spring metal plate 38 which is also of general triangular formation in contour. The said plate 38 is provided medially thereof with a concave inner edge portion 39 and with forwardly and rearwardly directed inner edge portions 40 and 41 which extend outwardly and at an angle to the outer side edge 42. The opposite ends of the plate 38 and the inner side edges adjacent the concave edge portion 39 are secured to the spring plate 29 by welding 43 or 10 other equivalent fastening means.

For the purpose of maintaining the arched plates 29 and 38 in longitudinal arched formation, the arch supporting unit 11 also includes a tension plate comprising oppositely disposed sections 44 and 45 which are spot-welded as at 46 or otherwise secured at their opposite ends to the ends of the arch plate 38. The inner ends of the sections 44 and 45 are disposed in overlapped relation and provided with a registering slot 47 adapted to receive a bolt 48 for selectively tensioning the tension plate so as to produce a differential upward arching of the arch plates 29 and 38.

25 The arch supporting units 10 and 11 are adapted to be positioned and selectively adjusted longitudinally and transversely of the sole of the shoe and angularly about a vertical pivotal connection consisting of a bolt 49 extending through any one of the openings 16 in the attaching member 15 and through any one of the openings 22 in the extension 21 of the upper member 19 with the inner end thereof engaged in the threaded opening 50 of an anchoring member 51 embedded in or secured to the sole of the shoe for 30 anchoring the units in relative adjusted relation.

35 In the form of the invention illustrated in Figs. 7 to 15 inclusive, the arch supporting unit 55 for the metatarsal arch and the arch supporting unit 56 for the longitudinal arch are of the same 40 general configuration in contour respectively as the units 10 and 11 in the previous embodiment. The arch supporting unit 55 includes upper and lower plies 57 and 58 respectively fashioned from leather, rubber or any analogous flexible material which are secured together adjacent their edges by stitching 59 or other equivalent means 45 so as to define a pocket therebetween, the lower ply 58 being provided with an arcuate slit 60 defining a mouth for introducing therethrough 50 filler pads 61 for producing a differential upward arching of the upper ply 57.

55 Secured to the outer surface of the lower ply 58 by rivets 62 or other securing means, is an attaching member 63 fashioned from deformable sheet metal, leather or any other equivalent material and which is provided with a plurality of longitudinally and transversely spaced openings 64 adjacent the rear thereof and underlying the shank portion of the said unit. The attaching member 63 is formed with an enlarged forward end which is provided with a plurality of forwardly extending flexible fingers 65 which overlie the mouth opening 60 and serve as a closure therefor.

60 The longitudinal arch supporting unit 56 includes an upper member 66 fashioned from deformable sheet metal, leather or any other equivalent material and extends from a point overlying a portion of the heel of the shoe to a point 70 alongside of the metatarsal arch supporting unit 55. The said member is of general triangular shape in contour with the forwardly and rearwardly directed inner side edge portions 67 and 68 extending outwardly and at an angle to the 75

outer side edge 69 and providing pointed front and rear terminals 70 and 71. Underlying the upper member 68 is a plurality of spring metal plates 72, 73 and 74 which are longitudinally arched with the highest point thereof under the inner longitudinal arch of the foot and substantially medially of the said plates, the said plates decreasing in height towards the opposite ends thereof and laterally towards the inwardly curved side edges. The plate 72 is of the same general contour as the spring metal plate 29 of the longitudinal arch supporting unit 11, while the plates 73 and 74 are the same general shape as the spring metal plate 38 of the longitudinal arch unit 11. The plate 73 is welded at its opposite ends and along the outer side edge as at 75 to the underside of the plate 72, while the plate 74 is likewise similarly welded as at 76 to the underside of the plate 73, the said plates when so united forming a resilient support for the upper member 68 and to which the spring plate 72 is welded or otherwise secured at its ends and along the inner side edge thereof as at 77 to the underside thereof. Underlying the said arch plates is a tension plate 78 which is of the same general shape in contour as the upper member 19 of the arch supporting unit 11 and is similarly provided with an inwardly directed lateral extension 79 formed with a plurality of longitudinally and transversely spaced openings 80 for selective registration thereof with the openings 64 of the attaching member 63 of the metatarsal arch support 55. The tension plate 78 is welded or otherwise secured at its ends to the ends of the spring metal plates 72, 73 and 74 and to the upper member 68 along the inwardly curved side edge as at 81. In order to provide means for producing a differential upward arching of the spring plates and the upper member 68, the tension plate 78 is formed substantially medially thereof with an arcuate slit 82 which slit merges with a laterally extending slit 83 forming furcations upon the upper surface of which the bifurcated ends 84 of a spring tongue 85 are welded or otherwise secured thereto as at 86. The spring tongue 85 protrudes through the arcuate slit 82 and is formed adjacent the outer end thereof with a rectangular slot 87 adapted to receive and hold against turning movement the kerfed head 88 of an upstanding bolt 89. The bolt 89 is engaged by a flanged nut 90 which protrudes through registering oblong openings 91 in the tension plate 78 and resilient reenforcing plate 92 which is welded as at 93 or otherwise secured to the upper surface thereof. Turning of the bolt 89 functions to produce a differential spacing of the longitudinal edge portion of the tension plate 78 from the free end of the tongue 85 which rests upon the upper surface of the insole of the shoe 60 and thereby a differential arching of the spring plates 72, 73 and 74 and the upper member 68. In order to turn the bolt 89 with reference to the nut 90, the kerfed head 88 is disengaged from the slot 87 and after the adjustment is made the head 88 is again reengaged with the opening 87 to lock the arch in adjusted position.

The arch supporting units 55 and 56 are adapted to be positioned upon the insole of a shoe and selectively adjusted longitudinally and transversely thereof and angularly about a bolt 94 extending through any one of the openings 64 of the arch support 55 and through any one of the openings 88 of the arch support 56 with the inner end of said bolt engaged in a threaded opening in an anchoring shank embedded in or

secured to the sole of the shoe, similar to the vertical pivotal connection of the bolt 49 of the arch supporting units 10 and 11.

In place of the metatarsal arch supporting units 10 and 55 in the previous forms of the invention, the metatarsal arch supporting unit illustrated in Figs. 16 to 19 inclusive may be employed. This metatarsal arch supporting unit includes a spring metal plate 97 of general oval formation in contour conforming generally to the region of the metatarsal arch of the foot and with a convex upper surface and a concave lower surface. The plate 97 is formed with pairs of rearwardly and forwardly extending arcuate slits 98 and 99 extending inwardly from the forward and rearward marginal edges thereof to define forwardly and rearwardly disposed tongues 100 and 101, the forward tongue 100 being longitudinally slotted medially thereof by a slit 102 extending inwardly from the forward edge thereof to a point adjacent the center. For the purpose of increasing the flexibility thereof, the said tongues are provided with substantially longitudinally extending slits 103, the outer ends of which are spaced from the marginal edges of the said tongues while the body of the plate is formed with longitudinally spaced, substantially transversely extending slits 104 with their outer ends spaced from the marginal edges of the laterally side edges of said plate. Underlying the plate 97 is a tension plate consisting of oppositely disposed sections 105 and 106, the forward section 105 having its outer edge contoured to the form of the forward edge of the tongue 100 and welded as at 107 or otherwise secured to the said tongue adjacent the forward edge thereof. The section 106 is similarly welded as at 108 or otherwise secured to the tongue 101 adjacent the outer edge thereof with the reduced inwardly extending portions of said sections overlapped and provided with registering slots 109 for receiving therethrough a bolt 110 adapted to adjustably secure the sections together for varying the stress on the said tongues 100 and 101 so as to produce a differential longitudinal and transverse upward arching of the plate 97. The section 106 is formed with a rearwardly extending shank portion 111 provided with longitudinally and transversely spaced openings 112 for selective engagement by the bolt 49 or 94 when employed in place of the arch supporting units 10 and 55 of the previous forms.

What is claimed is:

1. In a device of the character described, an arch supporting unit including a deformable metallic plate, a resilient arch plate underlying said deformable plate and connected therewith, a tension plate underlying said arch plate and connected therewith at its ends, one of said plates having an extension provided with a plurality of longitudinally and transversely spaced openings, and means adapted to engage with the sole of a shoe to selectively extend through any one of said openings for adjustably anchoring the unit to the shoe.
2. An arch supporting device in combination with a shoe having an anchoring member secured to the sole thereof and provided with a threaded opening, comprising a pair of arch supporting units each having an arched upper surface and each including a member provided with a plurality of longitudinally and transversely spaced openings, said members being adapted to be disposed in overlying relation one with the other to selectively register any one of the openings in one member with any one of the openings

in the other, and means adapted to extend through the registered openings and to engage with the threaded opening of the same anchoring member for anchoring the units to the sole 5 of the shoe.

3. An arch supporting device in combination with a shoe having a metal plate embedded in the sole thereof and provided with a threaded opening, comprising a pair of arch supporting 10 units each having an arched upper surface, means on said units provided with a plurality of longitudinally and transversely spaced openings adapted to be arranged in overlying relation to adjustably register any one of the openings 15 in one of the units with any one of the openings in the other unit, and means adapted to engage with the threaded opening in the metallic plate embedded in the sole of the shoe and to extend through the registered openings 20 in said units for anchoring the units in adjusted position in the sole of the shoe.

4. An arch supporting unit in combination with a shoe having a metal plate embedded in the sole thereof and provided with a threaded 25 opening, comprising a flexible member, a resilient arch plate underlying said member and connected therewith, a tension plate underlying said arch plate and connected therewith at its ends, one of said plates having an extension 30 provided with a plurality of longitudinally and transversely spaced openings, and means adapted to engage with the threaded opening in the metal plate embedded in the sole of the shoe and to selectively extend through any one of 35 said openings in said extension for adjustably anchoring the unit to the shoe.

5. In a device of the character described, an arch supporting unit including an arched upper member, a resilient arch plate underlying said 40 member and secured thereto at its ends, a tension plate underlying said arch plate and secured thereto at its ends for maintaining said arch member and said arch plate in arched formation, a tongue secured to said tension plate 45 and extending under the outer longitudinal edge portion thereof, and means engaging said tongue and said tension plate for producing a differential stress on the tension plate so as to

produce a differential upward arching of the arch plate and the upper arched member.

6. In a device of the character described, an arch supporting unit including an arched upper member, a resilient arch plate underlying said 5 member and secured thereto, a tension plate underlying said arch plate and secured thereto at its ends, means for producing a differential tensioning of the tension plate so as to produce a differential upward arching of the said upper member and the arch plate, said upper member having a plurality of spaced openings, and means adapted to selectively extend through any one of said openings and to engage with the sole of the shoe for adjustably anchoring the unit 10 15 thereto.

7. In a device of the character described, an arch supporting unit including an arched upper member, a resilient arch plate underlying said member and secured thereto at its ends, a tension plate underlying said arch plate and secured thereto at its ends for maintaining said upper member and arch plate in arched formation, said upper member having its highest point substantially centrally of its ends and decreasing 20 in height laterally towards the outer side edge thereof, said tension member being secured to the upper member at its ends and at points along the outer side edge thereof, and said tension plate being provided with a plurality of 25 openings, and means adapted to engage with the sole of the shoe to selectively extend through any one of said openings for adjustably anchoring the unit to the shoe.

8. In a device of the character described, an 35 arch supporting unit having a resilient arched upper plate, a tension plate underlying said arch plate, including a pair of sections adjustably connected together and respectively secured to the opposite ends of said arch plate, one section 40 thereof being provided with a rearward extension having a plurality of longitudinally and transversely spaced openings, and means adapted to engage with the sole of a shoe and to selectively extend through any one of said openings for adjustably anchoring the unit to the 45 shoe.

JOSEPH C. HOWELL.
